UNITED STATES PATENT OFFICE.

OSCAR T. LAY, OF GRASSY BUTTE, NORTH DAKOTA, ASSIGNOR OF ONE-THIRD TO
HENRY G. SCHWARTZ, OF KILLDEER, NORTH DAKOTA.

FARM GATE.

Application filed May 4, 1923. Serial No. 636,622.

To all whom it may concern:

Be it known that I, OSCAR T. LAY, a citizen of the United States, residing at Grassy Butte, in the county of McKenzie and State 5 of North Dakota, have invented certain new and useful Improvements in Farm Gates; and I do hereby declare the following to be a full, clear, and exact description of the invention, such as will enable others skilled in 10 the art to which it appertains to make and use the same.

The invention relates to gates and more particularly to a gate for closing an opening in a fence erected about a farm, garden 15 or other piece of land, and has for its object to mount the gate so that it may be swung at either end and in either direction, or be readily detached and set aside as required.

Other objects and advantages will be apparent and suggest themselves as the nature 20 of the invention is understood.

While the drawings illustrate an embodiment of the invention it is to be understood that in adapting the same to meet different 25 conditions and requirements, various changes in the form, proportion and minor details of construction may be resorted to without departing from the nature of the invention.

30 Referring to the accompanying drawings forming a part of the application:

Figure 1 is a front view of a gate embodying the invention, the dotted lines showing one of the posts elevated to release the 35 gate whereby it may be swung about the other post in either direction, as required.

Figure 2 is a top plan view, the dotted lines indicating different adjusted positions of the gate when swung from opposite ends 40 and in opposite directions.

Figure 3 is a sectional detail on the line 3-3 of Figure 1, and

Figure 4 is a detail view in elevation of a portion of one of the posts.

45 Corresponding and like parts are referred to in the following description and designated in the several views of the drawings by like reference characters.

The gate may be of any construction and 50 comprises end members 1, longitudinal elements 2, and cross braces 3. A post 4 is provided at each side of the gate opening

and the gate is so mounted as to swing at either end about either of the posts 4 and in either direction, as indicated by the 55 dotted lines in Figure 2. The lower ends of the posts 4 are stepped in base pieces 5 preferably formed of concrete and firmly set in the ground. A tube 6 is let into each of the base pieces 5 and receives the lower 60 end of the post. A tube 7 clamped to the end of the gate is adapted to rest upon the tube 6 and receive the post 4 which is 65 slideable therein and in the tube 6, said post being movable vertically by means of a handle 8 let into a side of the post and projecting through a slot 9 formed in a side of the tube 7.

The tube 7 may be secured to the ends 70 of the gate in any manner and, as shown, clamps 10 are provided and engage both the tube 7 and the end members 1 of the gate. The posts 4 move vertically in the tubes 6 and 7 and when both posts are lowered so as to enter the tube 6, the gate 75 is locked and cannot be opened at either end. However, when either one of the posts 4 is raised so as to clear the tube 6, the gate is free at such end and may be swung 80 open in either direction. The slot 9 in the 85 side of the tube 7 faces away from the gate opening and is in line with the fence, thereby admitting of the handle 8 being conveniently reached from either approach to the gate. It is observed that the gate may be 90 advantageously used for stock yards and in fact in any situation or place where a swinging gate is adapted for use.

What is claimed is:

A gate, a tube at each end of the gate 90 and having a longitudinal slot in a side thereof, a post movable in each of the tubes, a handle projecting laterally from each of the posts and passing through the longitudinal slot of a tube, a base for the lower 95 end of each post, and a tube let into the base and adapted to receive the lower end of the post.

In testimony whereof I affix my signature in presence of two witnesses.

OSCAR T. LAY.
